UNITED STATES PATENT OFFICE.

LORING J. BAKER, OF BOSTON, MASSACHUSETTS.

SELF-LEVELING BERTH.

SPECIFICATION forming part of Letters Patent No. 289,618, dated December 26, 1882.

Application filed August 24, 1882. (No model.)

To all whom it may concern:

Be it known that I, LORING J. BAKER, of Boston, in the county of Suffolk and State of Massachusetts, have invented a new and useful Improvement in Self-Leveling Berths; and I do hereby declare that the following is a full, clear, and exact description of the same.

My invention is an improvement in berths for ships and other sea-going craft of the class in which the berth is hinged so as to permit free motion and maintain a horizontal position when the ship pitches or rolls.

The improvements are more particularly applicable to the form of berth shown in an application filed by me in the United States Patent Office on the 4th day of May, 1882.

They relate, first, to an improvement in the transverse pivoting-rod of the berth, whereby the support is shifted to a point forward of the central pivoting-rod to compensate for the extra weight toward the head of the berth.

They relate, in the second place, to improved locking device for holding the berth in any given position.

In the third place the improvements relate to the supporting-bracket, whereby lateral rocking movement is permitted the berth, but longitudinal movement prevented.

They relate, fourth, to improved devices for suspending the rocking frame; and, fifth, to an improved mode of connecting the yokes and side bars.

In the accompanying drawings, Figure 1 represents a plan view of the berth; Fig. 2, a rear side elevation; Fig. 3, a section on line $\alpha\alpha$ of Fig. 1; Fig. 4, a longitudinal section on line yy , Fig. 1. Fig. 5 is a detached view of the bracket in plan and section. Fig. 6 is a view showing connection between side bars and yokes.

In these drawings, A represents the berth, of ordinary construction. It is supported directly upon a rod, b , on which it rocks in vertical longitudinal plane. This rod is fixed in side bars, $c c$, suspended by yokes $d d$, these being pivoted to the ends of the side bars.

In the construction shown in my said application the whole weight of the person occupying the berth was thrown upon the central transverse rod, b , and as the greater weight of the occupant is at the head it has been found necessary to place a weight at the foot of the berth in order to counterbalance this increased weight at the head.

In order to obviate the necessity of using weights, I have fixed to the rod b a strong arm, m , preferably toward the head. This arm is preferably a flat metallic bar, and is provided with two rows of holes, in which are set vertical pins n , and these pins may be set in any of the holes, so as to throw the weight nearer to or farther from the rod b . Upon the upper ends of these pins, which may be pointed, rest the inner edges of the bottom pieces or slats, $o o$, of the berth. The outer edges are supported in grooves or on beads on the edge of the bottom of the berth. The pins n are high enough to support these slats or bottom pieces a sufficient distance above the rod b to prevent them from touching said rod in any ordinary position of the berth. This throws the weight of the person upon the arm m , and consequently at a distance from said arm toward the head of the bed, and this distance may be regulated by the position of the pins according to the requirements of the occupant. The support being nearer the center of gravity, the berth is kept in horizontal position without the use of weights, and when the occupant leaves the berth it remains level, as it is then balanced on the bar. Instead of these pins, I may have an anti-friction roller or a spring.

In place of the notched bar and latch in my former application, I have provided as a simpler device a pivoted arm and a holding-screw. This arm is shown at p . It is a round rod fixed to a cross-piece, p' , which is pivoted in ears on the side of the state-room, the rod p being preferably in line with the rod b . The rod p passes through a hole in a block, q , moving freely therein when not held by the set-screw 2. Just below the hole through which the rod p passes in the block q is a transverse hole at right angles to the first, through which passes the rod r of the bracket R , the block q having free lateral movement upon the rod r . A loose pin, 3^a , is placed in a hole bored through from the hole which receives the rod p to that which receives the rod r , the pin being so adjusted that when the set-screw is pressed down on the rod p it shall through that rod press upon the pin and press the pin against the rod r , so that the set-screw may fix the block to both rods at the same time. The bracket R is attached to the under side of the rear of the berth, and the lower part is bent to the rear, so that the set-screw may rise without coming in contact with the

berth. It will be apparent that when the set-screw is loose the berth may swing laterally, the rod *p* slipping freely through the block *q*, which then turns upon the rod *r*, and when the berth swings longitudinally the block slides upon the rod *r*; but the same set-screw holds them in any position, and thus locks the berth against rocking or swinging in any direction.

I have also modified and simplified the device which holds the upper part of the berth. The bracket described in my former application, adapted for the purpose of pivoting the upper part of the berth and allowing it to swing laterally while giving an upper bearing-point for the longitudinal swing, consisted of a double-jointed bracket.

The device shown in this application consists of a bracket having two telescoping parts, the tubular part *S* being pivoted to the wall of the state-room by long bearings, while the part *s*, which carries the pivot 13, slides in the tubular part and permits lateral rocking movement of the berth, but no longitudinal movement of the pivot 13. This device is the same in operation as that described in my aforesaid application, but is of simpler construction.

In order to protect the feet and head of the occupant from contact with the yokes which support the berth, I attach to the foot and head a sheet, *F*, of artificial leather or some similar material which extends up and covers the said yokes, but which, as it is attached to the head and foot of the berth, moves with the berth and remains constantly in proper position.

In my former application heretofore referred to the rods or links by which the yoke was suspended from the ends of the state-rooms or walls were attached to the wall by fixed staples, thus maintaining the links always at the same angle.

It will be apparent from an inspection of Fig. 3 that the center of motion when the berth rocks laterally will be at a point where the lines of the rods prolonged would intersect. The ease with which the berth would rock would depend upon the distance of this point above the weight in the berth, the berth rocking more readily the longer the leverage between the point aforesaid and the weight below it. In order to adjust this at will I have provided adjustable supports for the upper ends of the links. These consist of plates *G G*, provided with slots 4, formed upon a curve, of which the point of intersection of the two links prolonged is the center. The plate *G* is provided with a hook, 5, the end of which is in line with the inner face of the plate, and which when the plate is set against the wall bears also against the wall and holds the link securely in place, as shown in Fig. 3. These plates are held to the wall by bolts set therein and nuts 6, which bear against the face of the plate. These plates may therefore be shifted readily to any required position. Ordinarily the rods will be inclined at an angle of about forty-five degrees from the perpendicular. I prefer

to connect the lower ends of the links to the yoke by means of two staples, 77, instead of one elongated staple. It will be understood, now, that the berth is permitted a free lateral movement, since the links can turn both at top and bottom in the hook 5 and staple 7, so that the relative position of such links will be changed according to the direction in which the berth oscillates. For instance, referring to Fig. 3, should the left side of the berth be depressed, the link on that side would approach a little nearer to the perpendicular, while the inclination of the other link would increase, as will be readily apparent.

Instead of connecting the side bars, *d d*, to the ends of the yokes by a pin passing through holes in the overlapping ends, I have provided an adjustable connection. (Shown in Figs. 2 and 6.) In this construction the end of the bar *d* has a series of notches, as shown at 8, and the ends of the yokes are provided with pins 9, over which the notched ends rest, with the pin in any desired notch. By means of this connection the inclination of the yokes may be changed and the longitudinal swing increased or diminished.

Having thus described my invention, what I claim is—

1. In combination with a berth and a transverse pivoting-rod supported on suitable side bars, an arm, *m*, projecting toward the head of the berth and provided with suitable supporting devices for the bed-bottom, substantially as described.

2. In combination with the berth, the pivoted rod *p*, adapted to swing in vertical plane, the bracket *R*, with the rod *r*, the perforated block *q*, and a device for holding the block in any position upon the rod *p*, and the rod *r*, substantially as described.

3. The combination of the pivoted rod *p*, adapted to swing in vertical plane, and the bracket *R r*, the block *q*, sliding upon these parts, as described, the set-screw *p'*, and the pin 3¹, substantially as described.

4. The combination of the berth, the yokes, and suitable intermediate supporting devices, the links and adjustable brackets, whereby the inclination of the links may be varied, substantially as described.

5. The combination of the yokes, supporting-links, the brackets *G*, having slots and hooks 5, and the side bars, *c*, the parts being connected to the wall and to the berth, substantially as described.

6. The combination of the berth with the notched side bars *c*, and the yokes having pins 9, such yokes being connected to the wall, substantially as described.

In testimony whereof I have signed my name to this specification in the presence of two subscribing witnesses.

LORING J. BAKER.
